MARK S. HOTCHKISS, OF JOHNSON CITY, NEW YORK.

WALL FORM.

Application filed November 23, 1925. Serial No. 70,816.

My invention relates to a form used in the construction of concrete walls for buildings, supports and other purposes.

The principal object of my invention is to construct a steel form for concrete construction work which is completely standardized as regards its parts, which is quickly and easily assembled and disassembled, and which forms a rigid, lateral, and vertical support for the pouring of concrete or other building material.

Another object is to provide a one piece plate or panel form unit, flanged on all sides so as to make it readily engageable with and removable from suitable supporting members in the building up of the desired forms.

A still further object is to provide a new type of corner construction for forms which may be readily assembled or removed and which insures accurate and properly aligned corners in concrete wall building.

Another object is to provide a novel means of support for rigidly holding the plate forms in their assembled position.

A further object is to provide a new tie rod for spacing the inner and outer walls of the forms, and for holding them against buckling or distortion.

Another object is to provide means at the juncture of adjacent plate forms for locking the tie rods against unauthorized displacement.

Still another object is to provide an adjustable brace for reinforcing the form and for bringing the same into proper alignment.

Another object is to provide the supporting members of the wall forms with means for securing a scaffolding thereto.

A further and important object is to provide the interconnecting parts of the wall form with ingenious connection means which not only secure the connected parts in proper relation, but which may also be easily and readily detached when it is desired to dismantle the form.

One further object is to provide means whereby the form may be carried upwardly to any desired height, the same being at all times properly braced and sufficiently strong to withstand the shocks and pressures placed upon it.

Other objects and advantages in details

of construction and operation will be apparent as the description proceeds, reference being had to the accompanying drawing wherein like reference numerals indicate like parts.

In the drawing:—

Figure 1 is a perspective view showing a section of my improved wall form in assembled position.

Figure 2 is a cross sectional plan view showing clearly the relation between the form plate and the supporting members when assembled, and also illustrating the method of locking the tie rods in position.

Figures 3 and 4 illustrate the method of removing the form plate from the supporting members by pivoting the plate in relation to the said members instead of sliding the same outwardly over the end of the adjacent supporting members.

Figure 5 is a detail sectional view of the inside corner of my improved form.

Figure 6 is similar to Figure 5, and illustrates the outside corner of the form.

Figure 7 is a side view from the left in Figure 6 showing the flange construction of the corner plate.

Figure 8 is similar to Figure 7 being taken from the right in Figure 6.

Figure 9 is a detail partly in section illustrating clearly my improved tie rod and its connection with the supporting members.

Figure 10 is a side view of the supporting member showing the key-hold attaching means provided for the tie rod.

Figure 11 is a modified form of tie rod.

Figure 12 is a detail partly in section illustrating the means of connection between the form plate and the supporting members.

Figure 13 is a detail, partly in section, illustrating the means of attaching the horizontal supporting bar, which may be used as a scaffolding support, to the supporting member.

Figure 14 is a detail plan view of one end of the horizontal brace member.

Figure 15 illustrates in detail the adjustable brace rod for the supporting members.

Figure 16 is a detail showing the method of connection between the adjustable brace rod and the supporting member.

Figure 17 is a detail showing the lower

end of the adjustable brace rod, adapted to rest on the ground or other supporting means.

The reference numeral 1 indicates a foot-
ing or foundation of concrete or other mate-
rial of suitable thickness, width and
strength for supporting the walls to be con-
structed thereon. Mounted in upright po-
sition and at suitably spaced intervals upon
10 the base 1, are the supporting members or
bars 2. These supporting bars are mounted
in spaced relation for both the inner and
outer forms for the proposed wall, the
inner and outer bars being directly opposite
15 one another.

The supporting bars are preferably made
out of heavy sheet metal, cold rolled or
otherwise pressed in the form of channel
20 bars having their channel portion 3 facing
inwardly and having their inner edges bent
outwardly to form laterally projecting
flanges 4 on either side. The flanges 4 lie
in the same flat plane and are parallel with
the flat surface of the channel 3.

25 The opposing supporting bars 2 are se-
cured together in spaced relation and held
against inward or outward displacement by
means of tie rods 5, which are preferably
of flat steel, and which are provided at each
30 end with notches 6. Each supporting bar 2
is provided at spaced intervals throughout
its length, with key notches or openings 7,
elongated laterally as shown clearly in Fig-
ure 10 through which the end of the tie rods
35 5 may pass when inserted flatwise. After
the tie rods have been inserted in this man-
ner and are again turned to the vertical
position as shown in Figure 9, it will be
seen that the supporting members 2 are se-
40 cured together and against inward or out-
ward movement with respect to the plane of
the inner or outer walls of the forms. As
shown in Figure 11, the tie rods 5 may be
modified by providing each end with a
45 single notch 6^A which may be hooked over
the lower edge of the key slot 7 in the sup-
porting bar.

50 The adjacent, upright supporting bars 2,
lying in the same plane, form guides for re-
ceiving the adjacent ends of panels or plates
8, and holding the latter against inward or
outward displacement in the manner about
55 to be described. The plate or panels 8 are
uniform in size and are preferably of heavy
steel or other material and are provided at
their ends with flanges, bent first outwardly
at right angles as at 9, then inwardly at
60 right angles as at 10, thus forming channels
at each end of the panel. As shown clearly
in Figures 3 and 4, the channels thus formed
engage over the flanges 4 of the supporting
bar 2, and lie within the channel 3 of the
65 supporting bar. The sides 9 of the adjacent
panels are thus brought closely together
within the channel 3, and between these

sides 9, as indicated in Figure 2, lies the
tie rod 5 which is thus prevented from turn-
ing flatwise when the form is assembled
and the panels are placed, thereby making
it impossible for the tie rods 5 to become
70 accidentally displaced. In such assembled
relation, it will be noted that the inner flat
surfaces of the panels 8 are brought sub-
stantially edge to edge in the same flat
plane, thus presenting a practically continu-
75 ous smooth surface on either side of the
form between which the concrete or other
building material may be poured.

The panels 11, which make up the cor-
ners of the wall form, are constructed at
one end in the manner just described, that
is with the flanges 9 and 10 for engage-
ment within the channels 3 of the adjacent
80 supporting bars 2. The opposite ends of
these corner panels 11, however, are formed
for engagement with each other as follows:
Referring particularly to Figures 1, 5, 6,
7 and 8, it will be noted that the left hand
panel 11 is provided at one end with a large
85 central flange 12 turned at right angles to
the body of the plate 11 for overlapping the
adjacent end of the right hand panel 11.
The right hand panel 11 is provided at one
end on the top and bottom thereof, with
90 flanges 13 turned at right angles to the body
of the panel for overlapping engagement
with the adjacent end of the left hand cor-
ner panel, and on opposite sides of the
flange 12. The adjacent corner panels may
95 be quickly and easily assembled by fold-
ing them inwardly towards each other and
hooking the interconnecting flanges 12 and
13 in their proper positions in respect to
each panel, and then folding the panels
100 outwardly until they are stopped by the
flanges engaging with the respective sides
of the panels. At this point, it will be
seen that the adjacent corner panels are
at right angles to each other and provide a
105 sharply defined corner for the walls. Due
to the close fit of these interconnecting
panels, a substantially unbroken form for
this corner is provided. It will be under-
stood also that if other than a right angled
110 corner is desired, the angle of the flanges
12 and 13 may be changed to suit.

115 Referring again to the panel 8, it will
be noted that the upper and lower edges
thereof are turned outwardly at right
angles to form the flanges 14, which form
supports for each panel and for the next
120 adjacent panel above, which rests upon it.
The end of the flanges 14 terminate just
short of the edge on the back turned flange
10 at the end of the panels. The ends of
the flanges 14 are also cut away slightly
125 adjacent the wall of the panel as at 15.
This cut away portion 15, and the space be-
tween the ends of the flanges 14 and the
flanges 10, provide space for receiving the
130

side walls of the supporting bars 2 and the flanges 4 thereof. From this construction, it will be observed that in assembling the wall form, the panel made may be slipped over the upper end of the supporting bars 2, the ends of the flanges 14 engaging with the flanges 4 of the supporting bars, and the flanges 9 and 10 of the panels assuming their position within the channels 3 of the supporting bars, whereupon the panels may be slipped downwardly along the length of the supporting bars, and one panel after another inserted in this manner, thus building up the wall by panels between the adjacent supporting bars. It will be also noted that as the panels are thus slipped into place, the tie rods 5 are automatically locked in securing position.

The corner panels 11 are provided with the flanges 14 also, at their upper and lower sides, one end of said flanges being formed with the cut out portion 15, as before described, but the opposite end thereof adjacent the corner is left square.

Although from the foregoing description, it is apparent that the panels 8 may be readily slipped up or down on the supporting bars 4 to assemble or dismantle the forms, it will also be apparent from Figures 3 and 4 that time may be saved in dismantling the form by simply pivoting the panels 8 outwardly and thus disengaging them from the adjacent support 2. The cut out portion 15 on the flange 14 is made at such an angle, and with rounded corners, as to permit disconnection between the panels 8 and the supporting bars 2 in this manner. It will be understood, of course, that before this can be done, one of the upright or supporting bars 2 must be removed. The construction just described facilitates the dismantling of the parts of the wall form which may then be taken to another part of the construction, or to another job for use over again.

It will be observed that all of the flanges on the various panels making up this wall form, are turned outwardly or away from the space between the forms into which the concrete is poured. Thus the inner surfaces of the form presented is substantially unbroken smooth surface for forming the concrete wall.

Bracing means is provided for the wall form to prevent its buckling or bulging outwardly or otherwise becoming distorted, or out of alignment. This bracing means includes an adjustable brace rod in two sections 15 and 16, one telescoping within the other. Each section is preferably made of channel iron or steel, and the sections may be adjusted longitudinally with respect to each other by a pin and slot connection 17, the pins thereof being provided with wing nuts or other suitable means for rigid-

ly securing the sections in adjusted position. This adjustable feature permits the brace to adapt itself to variations in the level or contour of the ground adjacent the wall, and provides for a uniform bracing of the wall throughout its length.

The upper end of the brace rod member 16, is provided with an integral centrally twisted nose member 18 for insertion within a vertically arranged key-hole slot 19 in the supporting bar 2.

From this construction, it will be seen that the brace rod may be turned upon its side and the end 18 thereof inserted in the slot 19, whereupon the brace may be turned back to its normal position, thus securing the same with relation to the upright supporting member 2. The lower end of the brace member is provided with an outwardly turned foot 20 provided with a stake opening 21 through which the stake 32 is driven into the ground for rigidly securing the brace in proper position. It will be noted that the foot 20 is also provided with additional openings 23, which may be used in case the brace is resting upon wood or other material wherein screws instead of a stake are necessary for securing the brace in position. This brace member is all metal in construction and is quickly and easily assembled and dismantled together with the rest of the metal wall form.

In practice, it is advisable to place the key-hole slot 19 for the reception of the brace member at intervals throughout the length of the supporting bars 2. This permits the use of longer or shorter brace rods as desired or both if it is necessary because of peculiar working conditions.

It will be noted that the length of the supporting bars 2 is such that the top set of panels which are engaged therewith extend slightly above the top of the supporting bars. This construction permits a second tier or story of supporting bars to be placed end to end upon the lower one, and the wall form then built on up in the same manner as herein indicated and described, a high as is practicable.

At the point of connection between such upper and lower layers of supporting bars, it will be noted that the panels adjacent such intersection or end to end connection overlap on the adjacent supporting bars and thus reinforce them. In such event the brace bars 15 and 16 would of course be much longer than the one indicated in order to reach from the top supporting rod to the ground. This construction has not been illustrated in view of the fact that it is a mere duplication of the parts herein shown and described and is believed to be clear without such duplication.

The upright bars 2 are also provided at intervals throughout their length with ver-

tical spaced slots 24 for the reception of the central integral twisted hooked ends of braces 25. These hooked ends are indicated at 26 and are clearly illustrated in Figures 13 and 14. The outer end of the brace bar 25, which extends horizontally outwardly from the wall forms, may be adjustably and rigidly secured to an upright brace 26, whereby additional support for the wall forms is provided. It will be noted with reference to Figure 1 that this construction also provides a support for scaffolding 27, which may be built up as high as the wall forms are constructed. The brace rod 25 is preferably of channel steel or iron, and as shown is as easily and quickly assembled or dismantled as is the rest of the units which make up this wall form.

From the foregoing, it will be seen that I have provided a section, metal form, preferably of steel, for use in the construction of walls, and which may be assembled and built up in any desired shape or formation, which is adequately braced at regular intervals with metal units which form part of the wall construction, the entire form being quickly and readily assembled without the use of any wooden parts or of nails or screws, and which may be both assembled and dismantled by an inexperienced workman. The facility with which a wall form of this kind can be built up will be readily understood by those skilled in the art. Time, labor, and materials are saved in large measure, and accuracy of alignment is insured. The majority of the parts making up the form are interchangeable, and may be used over and over again in construction work. The various parts when assembled are adequately locked against accidental displacement, the value of which is obvious. Most of the parts, particularly the bars and the panels, are so constructed that they may be easily and conveniently packed together for easy transportation.

While I have shown the preferred embodiment of my invention herein, I do not wish to be limited to the exact construction shown and described, other than by the appended claims, as it will be apparent that many changes in details of construction and operation may be made without departing from the spirit and scope of the invention.

I claim:

1. A wall form comprising an upright supporting bar having a channel and lateral flanges, a panel provided with vertical and horizontal flanges, one of said vertical flanges engaging within said channel and said horizontal flanges engaging one of said lateral flanges, whereby said panel is removably secured to said bar.

2. A wall form comprising a channeled upright supporting bar, lateral flanges on said bar, a panel having end flanges one of

which engages within said channel, the upper and lower edges of said panel provided with means for engaging one of said lateral flanges whereby said panel is removably secured to said bar.

3. A wall form comprising a channeled upright supporting bar, lateral flanges on said bar, a panel having end flanges, one of which engages within said channel, the upper and lower edges of said panel being flanged and provided with means for engaging one of said lateral flanges, whereby said panel is removably secured to said bar.

4. A wall form comprising a channeled upright supporting bar, lateral flanges on said bar, a panel having end flanges one of which engages within said channel, the upper edge of said panel being flanged and provided with means for engaging one of said lateral flanges whereby said panel is removably secured to said bar.

5. A wall form comprising a channeled upright supporting bar, lateral flanges thereon, a panel having end flanges one of which engages within said channel, the lower edge of said panel being flanged and provided with means for engaging one of said lateral flanges whereby said panel is removably secured to said bar.

6. A wall form comprising a channeled upright supporting bar, lateral flanges thereon, a panel having its ends channeled for engaging within said first mentioned channel, the top and bottom edges of said panel being flanged for engagement with said lateral flanges whereby said panel is removably secured to said bar.

7. A wall form comprising an upright supporting bar, a panel having means on its ends for engagement with said bar, the top and bottom edges of said panel being flanged, and the ends of said flanges being provided with means for engaging said bar whereby said panel is removably secured to said bar.

8. A wall form comprising an upright supporting bar, a panel having means on its ends for engagement with said bar, the top and bottom edges of said panel being flanged and the ends of said flanges being recessed between the edges of said flanges and said panel to provide means for removable engagement with said bar.

9. A panel for wall forms comprising a one piece plate provided at its ends with channel flanges and at its top and bottom edges with lateral flanges, said lateral flanges being recessed at their ends between the edges of said flanges and said plate to form an attaching and guiding means.

10. A wall form comprising an upright channeled supporting bar, a panel having channel flanges on its ends for engagement with said bar, the top and bottom edges of said panel being flanged and the ends of said

flanges being cut away adjacent said panel to form an attaching and guiding recess between said panel and said bar, said cut-away portion permitting disengagement of the panel and bar by pivoting said panel laterally of said bar.

11. A wall form comprising an upright supporting bar, a panel having one end removably engaged with said bar and the opposite end flanged for interlocking engagement with a second panel mounted adjacent and at an angle thereto.

12. A wall form comprising a pair of upright supporting bars, spaced apart and facing at an angle to each other, panels each having one end removably engaged with its adjacent bar and the opposite ends provided with interlocking flanges.

13. A wall form comprising a pair of spaced upright supporting bars facing at an angle to each other, panels engageable at one end with said bars, the opposite end of one of said panels being provided with a single central flange overlapping the end of the adjacent panel and the other panel having two spaced flanges overlapping the first panel on either side of said central flange.

14. Wall form corner panels comprising two plates disposed at an angle to each other, the outer ends of said plates provided with channel flanges and the adjacent ends of said plates having interlocking flanges.

15. Wall form corner panels comprising two plates disposed at an angle to each other, the outer ends of said plates provided with channel flanges and the adjacent ends of said plates having interlocking flanges, said flanges comprising a large central flange on one plate and two spaced flanges on the other plate for engagement on either side of said central flange.

16. Wall form corner panels comprising two plates disposed at an angle to each other, the outer ends of said plates provided with channel flanges and the adjacent ends of said plates having interlocking flanges, said flanges comprising a large central flange on one plate and two spaced flanges on the other plate for engagement on either side of said central flange, said plates also having top and bottom supporting flanges.

17. A wall form comprising two rows of spaced parallel upright supporting bars, the bars in each row being directly opposite each other, tie rods for connecting the opposing bars comprising flat strips provided with notched ends, and key slots in said bars for receiving said notched ends.

18. A wall form comprising two rows of spaced parallel upright supporting bars, the bars in each row being directly opposite each other, inwardly facing channels in said bars, panels having flanges engaging within said channels, key slots in said bars, tie rods comprising flat strips provided with notched

ends engaging in said key slots, the adjacent flanges of said panels within said channels locking said tie rods in vertical position.

19. A wall form comprising upright supporting bars, panels supported thereby, each of said bars provided with a key slot for receiving a removable one piece brace rod, one integral end of said rod being reduced and extending at right angles to the body of said rod, for engagement within said key slot. 70 75

20. A wall form comprising upright supporting bars, panels supported thereby, each of said bars provided with a key slot for receiving a removable brace rod, one end of said rod being reduced and extending at right angles to the body of said rod, for engagement within said key slot, said rod comprising two sections adjustable lengthwise with respect to each other. 80

21. A wall form comprising upright supporting bars, panels supported thereby, each of said bars provided with a key slot for receiving a removable brace rod, one end of said rod being reduced and extending at right angles to the body of said rod, for engagement within said key slot, said rod comprising two channeled sections adjustable lengthwise with respect to each other, and means for locking said sections in adjusted position. 85

22. A wall form comprising upright supporting bars, panels supported thereby, each of said bars provided with a key slot for receiving a removable brace rod, one end of said rod being reduced and extending at right angles to the body of said rod, for engagement within said key slot, said rod comprising two channeled sections adjustable lengthwise with respect to each other, and means for locking said sections in adjusted position, the lower end of the rod being provided with an angular attaching foot. 100 105

23. A wall form comprising upright supporting bars, panels supported thereby, each of said bars provided with a key slot for receiving a removable brace rod, one end of said rod being reduced and extending at right angles to the body of said rod, for engagement within said key slot, said rod comprising two channeled sections adjustable lengthwise with respect to each other, and means for locking said sections in adjusted position, the lower end of the rod being provided with an angular attaching foot, having a fastener receiving opening therein. 110 115

24. A wall form comprising upright supporting bars, panels removably supported thereby, each of said bars provided with key slots for receiving brace members, an angular brace member and a horizontal brace member each having one end engaged within said key slots, and a second upright member spaced from said bars for supporting the opposite end of said horizontal brace member. 120 125 130

25. A wall form comprising upright supporting bars, removable panels supported thereby, a slot in the outer face of each of said bars, a one piece horizontal brace member provided at one end with an integral twisted hook portion for engagement within said slot, and supporting means for the outer end of said member.

26. A wall form comprising a base upright supporting bars resting on said base 10 brace means for said bars rows of removable panels supported by said bars, the top row of said panels extending above the upper end of said bars for substantially half the width of the panels.

MARK S. HOTCHKISS.
